DETERGENT DISPENSER

Frank T. Hilliker, St. Louis, Mo.

Application May 28, 1949, Serial No. 96,075

3 Claims. (Cl. 134—93)

1

This invention relates in general to certain new and useful improvements in detergent dispensers.

In various types of commercial washing machines, such as dishwashing equipment commonly used in restaurants, laundry apparatus, and the like, the washing operations are carried out automatically, but it has generally been considered necessary to introduce detergent material, such as trisodium phosphate, powdered soap, or synthetic surface-active agent, into the machine by hand. With the increasing use of comparatively extensive synthetic detergents, hand measuring procedure is extremely costly and wasteful in addition to being unreliable and creating unnecessary labor cost by reason of requiring comparatively close attendance of an operator.

It is, therefore, one of the principal objects of the present invention to provide a dispenser for discharging granular, pulverulant, or powdered materials into a soap-consuming machine, such as a dishwasher or the like.

It is a further object of the present invention to provide a dispenser of the type stated which is simple and economical in construction and is fully automatic in operation.

It is an additional object of the present invention to provide a dispenser of the type stated which will feed detergent material in measured proportion to the influx of fresh water into the detergent-consuming machine.

It is also an object of the present invention to provide a detergent dispensing device which will not become clogged in use and in which the granular, pulverulant, or powdered detergent material will not be dampened or otherwise adversely affected by moisture or water vapor from the detergent-consuming machine with which the dispenser is associated.

It is a further object of the present invention to provide a dispenser of the type stated which may be regulated to permit the discharge of an amount of detergent proportionate to the amount of water entering the machine whereby the dispenser may be efficiently utilized without regard to line pressure of the water.

It is an additional object of the present invention to provide a dispenser of the type stated which is fabricated of relatively few parts, thereby achieving economy in manufacture and simplicity in installation.

With the above and other objects in view, my invention resides in the novel features of form, construction, arrangement, and combination of parts presently described and pointed out in the claims.

In the accompanying drawings (two sheets)—

2

Figure 1 is a perspective view of a detergent dispenser constructed in accordance with and embodying the present invention;

Figure 2 is a transverse sectional view taken along line 2—2 of Figure 1;

Figures 3, 4, and 5 are transverse sectional views taken along lines 3—3, 4—4, and 5—5, respectively, of Figure 2;

Figure 6 is a transverse sectional view taken along line 6—6 of Figure 4; and

Figure 7 is a transverse sectional view taken along line 7—7 of Figure 2.

Referring now in more detail and by reference characters to the drawings, which illustrate a preferred embodiment of the present invention, A designates a conventional type of dishwashing machine and B designates a powdered or granulated detergent dispenser comprising a cylindrical container 1 having a removable top 2, said container 1 being disposed upon a conical hopper 3 the wall 4 of which converges downwardly into a neck portion 5 terminating spacedly above the top surface of the dishwashing machine A. Integrally formed with one section of the neck portion 5 and depending therefrom is a transversely extending wall member 6, the lateral margins of which are integral with outwardly projecting parallel side walls 7, 7'. Along their upper margins, the side walls 7, 7', are integral with the wall 4 of the hopper 3 and are integrally connected at their upper ends by a transverse boss 8 formed upon the wall 4 of the hopper 3. The wall member 6 and the side walls 7, 7', with their lower margins resting upon the upper surface of the dishwashing machine A, provide a housing 9 which may be enclosed by a plate 10 removably disposed upon and extending between the outer margins of the side walls 7, 7', and being secured by bolts 11 extending through suitable aligned apertures in the plate 10 and the boss 8. The lower end of the plate 10, when in closure-forming position, extends into a slot 12 formed by the outer margins of the side walls 7, 7', and a transverse wall section 13 of a support bracket or casting 14 having side walls 15, 15', which supportingly abut against the lower portions of the side walls 7, 7', of the housing 9 and are secured thereto by screws 16, and an inner wall section 17 abutting surfacewise against the transverse wall 6.

Suitably mounted within the housing 9 is an electric motor 18 having a shaft 19 projecting inwardly into the neck portion 5 of the hopper 3 through aligned apertures 20, 21, in the neck portion 5 and a vertically extending section 22 of a boss 23, integrally formed with the hopper

3, having its upper wall 24 continuous with the wall 4 of the hopper 3 and being provided with a weight-reducing recess 25. Secured for rotation with the shaft 25 by a pin 26 is the diametrically reduced end of a hexagonal feeder member 27 which projects across the area between the boss 23 and the diametrically opposite section of the neck portion 5. At its other end, the feeder 27 is provided with an inwardly extending threaded recess 28 for receiving the diametrically reduced end of a screw 29 which projects outwardly through an aperture 30 in the neck portion 5 in alignment with the apertures 20, 21. Integral with the lower margin of the neck portion 5 is an inwardly extending arcuate flange 31 which thus restricts the opening or discharge orifice 32 at the lower end of the hopper 3. Swingably disposed beneath the orifice 32 is a flow-metering plate 33 having a forwardly presented cut-off edge 34 and being pivoted upon a screw 35, which is threaded upwardly into a boss 36 integrally depending from the wall 4 of the hopper 3. It is thus to be seen that, upon swinging of the plate 33, the effective opening of the orifice 32 may be regulated for permitting desired amounts of the detergent to flow therethrough.

The electric motor 18 is connected by an electric cable 37 in parallel with a solenoid stop valve 38 positioned preferably upon the top surface of the dishwashing machine A adjacent the hopper 3 and having extending therethrough a water line 39 connected to a source of water (not shown) and discharging into the dishwashing machine A through a suitable aperture 40 in the top surface thereof. The valve 38 is controlled through the electrical line 41 by a remote switch (not shown), such as a conventional float switch, for example, if it is desired to control the water level in the dishwasher A. It will thus be seen that, upon flow-producing actuation of the valve 38, water will flow from the source (not shown) and into the dishwashing machine A and, simultaneously, the electric motor 18 will be energized, thereby rotating the feeder member 27 and causing detergent to be discharged from the hopper 3 through the orifice 32.

Detergent thus discharged descends into an annular basin 42 having a dished floor 42' provided in an inwardly projecting rounded portion of the casting 14. Adjacent said basin 42, the casting 14 is provided with a boss-like portion 43 having a passage 44 for projection therethrough of a flexible bleed-line 45, which, at its inner end, is diametrically reduced and projects tangentially into the basin 42 and at its other or outer end is connected to the water line 39, as at 46. The boss-like portion 43 of the casting 14 is further provided with an internally threaded passage 47 to receive an adjusting screw 48 having a nut 48' and abutting at its inner end against the flexible bleed-line 45 for restricting the flow of water therethrough for reasons appearing more fully hereinafter.

Integral with and depending from the basin 42 is an externally threaded stem 49 extending downwardly through an aperture 50 in the top surface of the dishwashing machine A and having disposed therearound a washer 51 held abuttingly against the underface of the top of the machine A by a nut 52. The stem 49 is provided with an axial passage 53 for conducting detergent and water to the interior of the machine A, said passage 53 opening at its upper end in the basin 42 through a centrally elevated portion 54 of the

floor 42' thereof. Extending diametrically across the upper end of the passage 53 is an integral filament 55 supporting a small sleeve 56 located co-axially within the passage 53 for receiving the rod-like leg 57 of an umbrella-like trap plate 58. When the plate 58 rests upon the sleeve 56, its peripheral margin will extend down into the annular basin 42 in upwardly spaced relation to the floor 42' thereof, as best seen in Figure 2 and for purposes presently more fully appearing.

In operation, with the solenoid stop valve 38 in open position, water is discharged into the machine A and a portion thereof will pass through the bleed-line 45 into the basin 42, creating a moderate turbulence therein as a result of the tangency of the axis of the line 45 to the basin 42. Water so entering the basin 42 will cover the floor 42' thereof and overflow downwardly through the passage 53 of the stem 49. Detergent discharged from the orifice 32 will fall upon the upper surface of the plate 58 of the trap 56 and be sluiced downwardly through the passage 53 by the water issuing from the line 45 for ultimate admixture with the fresh water entering the machine A. When the flow of water is cut off through closure of the valve 38, the flow of water through the bleed-line 45 will also stop and the motor 18 will cease rotating, so that dispensing action will concurrently stop. Because of the unique shape of the basin 42, sufficient water will remain therein to cover the lower margin of the plate 58, thereby forming a trap to prevent upward escape of moisture, vapor, or steam from the dishwashing machine A through the passage 53. The plate 58 of the trap member 56 thus acts as a shield between the incoming detergent and any vapors as might escape from the machine A, thereby effectively preventing the formation of any clogging mass of detergent.

In the event the amount of water passing through the line 45 into the basin 42 should be excessive, as where the source of water is under high pressure, the adjustment screw 48 may be threaded inwardly to compress the flexible sides of the bleed-line 45 for restricting the flow therethrough.

Since the amount of water per unit of time discharged into the machine A through the line 49 is dependent upon the particular pressure at the source, it is necessary to regulate the flow of detergent through the orifice 32 in order that the proportion of detergent to the quantity of water be maintained at any predetermined ratio. The plate 33 may accordingly be rotated to limit the effective opening of the orifice 32, so that the requisite amount of detergent will be discharged. To determine whether the desired amount of detergent is entering the machine A, various so-called "dry runs" may be made with the plate 33 at different settings. Thus, the wash water in the machine A will at all times have the proper amount of detergent therein regardless of the particular line pressure of the water and coincidentally effect a maximum economy of detergent. Finally, the water issuing from the bleed-line 45, to sluice the detergent into the machine A, preliminarily wets the detergent so as to start the process of dissolution, thereby materially accelerating the rate at which the detergent goes into solution when it reaches the main body of water in the machine A, and effecting great economy in terms of detergent-consumption.

It should be understood that changes and modifications in the form, construction, arrangement, and combination of the several parts of

the detergent dispenser may be made and substituted for those herein shown and described without departing from the nature and principle of my invention.

Having thus described my invention, what I claim and desire to secure by Letters Patent is:

1. For use with a machine having a substantially closed chamber in which washing operations may be carried out, a detergent dispenser comprising a hopper mounted exteriorly of said chamber so as to be substantially unaffected by the steam, spray, and other moisture laden fumes within the chamber, said hopper being provided with a discharge aperture and means for ejecting detergent through the discharge aperture, a dish-like receptacle disposed in downwardly spaced relation to the discharge aperture and having a central discharge spout opening downwardly into the chamber, said dish being provided around said spout with an annular depressed channel the upper level of which is approximately flush with the uppermost portion of the spout so that when liquid is charged into said channel the liquid will only discharge into the spout when it rises above said level, a canopy-like element mounted across and in upwardly spaced relation to the discharge spout and having a continuous peripheral margin which projects downwardly into said channel substantially below the upper liquid level thereof so as to form a trap preventing escape through the spout of steam, spray, and moisture laden fumes from the interior of the chamber, and means for introducing a stream of liquid into the bottom of said channel for flushing out the detergent deposited therein.

2. For use with a machine having a substantially closed chamber in which washing operations may be carried out, a detergent dispenser comprising a hopper mounted exteriorly of said chamber so as to be substantially unaffected by the steam, spray, and other moisture laden fumes within the chamber, said hopper being provided with a discharge aperture and means for ejecting detergent through the discharge aperture, a dish-like receptacle disposed in downwardly spaced relation to the discharge aperture and having a central discharge spout opening downwardly into the chamber, said dish being provided around said spout with an annular depressed channel the upper level of which is approximately flush with the uppermost portion of the spout so that when liquid is charged into said channel the liquid will only discharge into the spout when it rises above said level, a canopy-like element mounted across and in upwardly spaced relation to the discharge spout and having a continuous peripheral margin which projects downwardly into said channel substantially below the upper liquid level thereof so as to form a trap preventing escape through

the spout of steam, spray, and moisture laden fumes from the interior of the chamber, and means for introducing a stream of liquid tangentially into the bottom of said channel for flushing out the detergent deposited therein.

3. For use with a machine having a substantially closed chamber in which washing operations may be carried out, a detergent dispenser comprising a hopper mounted exteriorly of said chamber so as to be substantially unaffected by the steam, spray, and other moisture laden fumes within the chamber, said hopper being provided with a discharge aperture and means for ejecting detergent through the discharge aperture, a dish-like receptacle disposed in downwardly spaced relation to the discharge aperture and having a central discharge spout opening downwardly into the chamber, said dish being provided around said spout with an annular depressed channel the upper level of which is approximately flush with the uppermost portion of the spout so that when liquid is charged into said channel the liquid will only discharge into the spout when it rises above said level, a canopy-like element mounted across and in upwardly spaced relation to the discharge spout and having a continuous peripheral margin which projects downwardly into said channel substantially below the upper liquid level thereof so as to form a trap preventing escape through the spout of steam, spray, and moisture laden fumes from the interior of the chamber, and means for introducing a stream of liquid tangentially into the bottom of said channel for flushing out the detergent deposited therein, the outer side walls of said receptacle being substantially higher than the uppermost level of the canopy-like element so that the whirling stream of liquid which circulates around the channel from the tangential input means can flow upwardly and circulate near the top of the canopy-like element to flush the detergent cleanly therefrom.
